United States Patent [19]
Linzer

[11] Patent Number: Des. 288,910
[45] Date of Patent: ** Mar. 24, 1987

[54] ONE-TO-ONE FORCE-BALANCE FLUID
PRESSURE SENSOR COMPONENT

[76] Inventor: Irwin P. Linzer, 175 Welsh Rd.,
Lebanon, N.J. 08883

[**] Term: 14 Years

[21] Appl. No.: 680,324

[22] Filed: Dec. 10, 1984

[57] CLAIM

The ornamental design for a one-to-one force-balance
fluid pressure sensor component, as shown.

DESCRIPTION

FIG. 1 is a left front perspective view of a one-to-one
force-balance fluid pressure sensor component showing
my new design;

FIG. 2 is a front elevational view thereof;

FIG. 3 is a rear elevational view thereof;

FIG. 4 is a right side elevational view thereof;

FIG. 5 is a top plan view thereof;

FIG. 6 is a bottom plan view thereof.

FIG. 1

FIG. 2

FIG. 3

FIG. 4

FIG. 5

FIG. 6
